(57) **CLAIM**

The ornamental design for a straddle bone plate as shown and described.

DESCRIPTION

FIG. 1 is a front, top perspective view of a straddle bone plate comprising the new design;

FIG. 2 is a back, bottom perspective view of the design of FIG. 1;

FIG. 3 is a front elevational view of the design of FIG. 1;

FIG. 4 is a right side, elevational view of the design of FIG. 1;

FIG. 5 is a left side, elevational view of the design of FIG. 1;

FIG. 6 is a back elevational view of the design of FIG. 1;

FIG. 7 is a top view of the design of FIG. 1; and,

FIG. 8 is a bottom view of the design of FIG. 1.

The broken lines in the drawings represent portions of the straddle bone plate that form no part of the claimed design.

1 Claim, 6 Drawing Sheets
